CLAIM

The ornamental design for an electronic device cover, as shown and described.

DESCRIPTION

FIG. 1 is a top, back perspective view of an electronic device cover with a handle/stand in a fully closed position;
FIG. 2 is a top, front perspective view thereof;
FIG. 3 is a front view thereof;
FIG. 4 is a back view thereof;
FIG. 5 is a right-side view thereof;
FIG. 6 is a left-side view thereof;
FIG. 7 is a top view thereof; and,
FIG. 8 is a bottom view thereof.

The dashed broken lines depict portions of the electronic device cover that form no part of the claimed design. The dot-dashed broken lines represent boundaries of the claimed electronic device cover and form no part of the claimed design.
